UNITED STATES PATENT OFFICE.

JOHN E. BRELSFORD AND JOHN W. LUTZ, OF DAYTON, OHIO.

LIGHTNING-ARRESTER.

No. 829,055.

Specification of Letters Patent. Patented Aug. 21, 1906.

Application filed January 30, 1905. Serial No. 243,318.

To all whom it may concern:

Be it known that we, JOHN E. BRELSFORD and JOHN W. LUTZ, citizens of the United States, residing at Dayton, in the county of 5 Montgomery and State of Ohio, have invented certain new and useful Improvements in Lightning-Arresters; and we do hereby declare the following to be a full, clear, and exact description of the invention, such as will 10 enable others skilled in the art to which it app- pertains to make and use the same.

This invention relates to those devices, commonly known as "lightning-arresters," used for grounding or discharging excessive 15 potential charges from electrical lines for protection of instruments of fine and delicate mechanism, as in telegraphic, telephonic, and electric-lighting circuits, and especially for guarding the line from the effects of lightning 20 or atmospheric electricity or other induced charges of high potential.

Important objects attained by the invention are, first, sensitiveness or nicety of action in such devices, enabling the setting of 25 the electrodes to allow uninterrupted passage of current of a certain potential or the regular current having a desired voltage for performing the necessary work or for operating apparatus on the line and to ground or 30 discharge any dangerous overload or surplus current or charge of higher potential, thus insuring perfect protection for delicate instruments by uninterrupted flow of the regular current and arrest or cut out of any charge 35 of excessive potential; second, simplicity of construction and the provision of a device which can be readily applied by a single workman at any point on the line-wire without cutting the wire for protection of elec- 40 trical apparatus; third, safety and protection against injury or fire from sparks or flashes caused by the arc of currents of high tension, as where a lightning-bolt or other induced current strikes the wire; fourth, 45 avoidance of any permanent ground or discharge of the normal current by short-circuiting from rain, sleet, dust, or scale by thorough protection of the mechanism of the device from these elements.

50 A preferred embodiment of the invention is illustrated in the accompanying drawings, which form a part of this specification and with reference to which the invention will be 55 fully described, and then particularly pointed out and defined in the following claims.

In said drawings, Figure 1 is a side elevation of the device shown in electrical connection with the line-wire and ground-wire, and Fig. 2 is a central vertical section of the same. Fig. 3 is a top view of the cap.

The mechanism of the device comprises three distinct parts—viz., the cap A, the ground-rod B, and the insulation C, connecting them. These parts assembled form a rigid unitary structure. The cap and ground-rod may be of any suitable metal or other appropriate conductive material, preferably brass or steel. The insulation may be made of vulcanized rubber, porcelain, lava, or other firm and enduring non-conductive ma- 60 65 terial.

The cap A has a depending stud or projection a, preferably circular, with a squared-off end or flat terminal surface. This constitutes the line-electrode of the arrester, the 70 cap being in direct contact with the line-wire. Preferably the cap has also a depending peripheral flange, as at a', which embraces the upper beveled or reduced end of the insulat- 75 ing-shell C.

The ground-rod B is a hollow tube whose upper end b constitutes the other electrode and is serrated or furnished with points or 80 projections, preferably V-shaped points, having their extremities equidistant from and in close proximity to, but not in contact with, the flat end of the stud or electrode a.

The insulation C is a tubular shell inclosing and connecting the stud a of the cap and the upper part of the ground-rod. It may 90 be secured to these parts by transverse pins, as at c and c', or otherwise rigidly fastened thereto. Preferably a substantial length of the rod is contained in this shell or covering—say about an inch and a half or two inches or 95 more. The outer diameter of the shell is desirably the same as that of the cap; but its upper end is formed to fit in the concavity in the under side of the cap, whose flange a' embraces the top peripheral edge of the 100 shell, forming an air-tight and water-tight joint, which is the only exposed joint in the device.

As stated, the cap A is designed for direct contact with the line-wire, which is designated by the symbol x. For this purpose said cap has preferably a groove across its top to receive said wire, which is seated therein and secured by a tie-wire y, inserted through a transverse hole in the cap and having its 105

ends wound or twisted around the line-wire. This makes a simple and convenient means of installing the device in the line, a safe and secure fastening, and a perfect contact with the line-wire upon which the current is turned. Obviously a single workman can easily and quickly apply the device at any desired point on the line-wire merely by inserting a tie through the cap and then fastening it in close contact to the wire in the manner explained without expense, difficulties, and objections incident to cutting, splicing, or soldering the line-wire. The point in the line where the device is installed depends, of course, upon the position of the instrument or instruments to be guarded, the device being connected in advance of such apparatus to prevent the passage of any overload or current of excessive potential. The ground-rod B is adapted for electrical connection with the ground-wire z, which may be connected thereto by any secure and conveniently-manipulated means. For example, a binding-screw may be employed or the ground-wire may be inserted through a hole in the rod and have its end wound around the same. A further mode suggested is to solder the ground-wire in a groove cut in the rod. This may be done in the shop where the device is manufactured.

In operation the regular current flows uninterruptedly over the line-wire and through the cap A, while any current of excessive potential (according to the initial adjustment or setting of the electrodes, as hereinafter explained) leaks or arcs across the gap between a and b and discharges to the ground in the usual manner. The cap A is preferably considerably larger than the line-wire—say six or more times as large—having thus a larger relative capacity.

The construction and relation of the electrodes results in very effective and accurate operation, and this is deemed an important feature of our invention, for the lower end of the electrode a has a flat, smooth, or plain surface evenly charged, while the upper end of the coacting electrode b has its points or projections in close proximity to such surface. This causes a rapid and easy discharge or arcing between the electrodes, and it allows setting or initial adjustment of the electrodes to a very fine degree, since the points of b can be arranged so closely to the surface of a as to nearly contact. The same effect is gained as would be obtained by actual projections on both electrodes in the same intimate electrical relation, if that were possible, for it is only conceivable in theory, but impossible in practice—that is, the actual points on b produce electrical points on a, the latter coinciding with the former or occupying the same spaces or fields. Moreover, it is to be noted that the electrical density is greatest at the lower periphery of the electrode a, it be-

ing well known that electrical distribution is nearly uniform for a plain disk surface except at its periphery, where the density is a maximum. In our device, wherein the ground-rod is preferably of substantially the same diameter as the stud a, the points of the electrode b consequently project into the region of greatest density. Furthermore, by virtue of the hollow electrode b there are two surfaces exposed to electrical action, the inside and outside surfaces of the ground-rod, thus doubling the surface of the usual devices. The hollow ground-rod also renders the device safest against accidental fires resulting from overcharged wires, for in the event of the jumping of the current and production of an arc the spark will die out by the time it reaches the lower end of the ground-rod. The total length of the ground-rod should be adequate for this protection, preferably two or three inches or more, whereas the stud a on the cap may be very short. The arc within the insulating-tube causes the air to expand and tends thereby to expel the arc downward through the tube.

The electrodes can be arranged to meet any and all requirements—that is, to act for higher or lower excess voltage, as the nature of the case may demand. For protection of delicate mechanism the electrodes are preferably set in such close relation as to almost contact.

The insulating outer shell or covering C performs four separate and distinct functions: first, rigid connection between the parts, holding the electrodes a and b in constant relation; second, insulation allowing a certain desired current to pass at all times over the line-wire, but never an overload; third, protective covering and insurance against grounding the line-wire by rain, snow, sleet, ice, dust, or scale by virtue of the housing of the electrodes and the fluid-tight joint at a', and, fourth, confinement of the arcing within the shell as well as within the hollow ground-rod, so that when a lightning-bolt or other charge of high tension is induced in the line-wire the flash or sparks will die out before reaching the lower end of the ground-rod, thus making a safe device to place in or on buildings and secure against causing fire. We thus provide an effective device of extreme simplicity having the minimum number of parts attainable, fulfilling the several objects primarily stated, and adapted to be installed by a simple means of direct fastening to the line-wire. As before stated, this means for direct fastening is one of the important features of the invention. We do not limit ourselves, however, to the precise construction or means therefor explained, for we contemplate obtaining such direct attachment of the cap in other ways, as by soldering it to the line-wire or by using a split cap or a two-part cap and fastening it.

by means of a set screw or screws or by soldering.

It will be understood that the device is susceptible of modifications in details and that certain of its separate features exclusive of the entire combination, as well as such combination independent of the specific features, are all embraced within the scope of our invention as defined in the following claims.

10 It will also be understood that the ground-wire, while presumably connected with the earth, may be in some cases successfully connected with some other reservoir or conductor having capacity for absorbing the electricity 15 or current discharged from the main line, and hence the words "ground," "ground-line," and "ground-rod" in the claims will be construed with this significance in view.

We claim as our invention and desire to 20 secure by Letters Patent of the United States—

1. An arrester having, in combination, opposing electrodes, one of which is tubular and has terminal points, while the other has a 25 smooth terminal surface in close proximity to but not in contact with said points.

2. An arrester having, in combination, an electrode for electrical connection with the line conductor having a flat terminal surface, 30 and an opposed electrode for electrical connection with the ground, the latter electrode comprising a hollow rod or tube having its terminal furnished with points in proximity to but out of contact with said flat surface.

35 3. An arrester having, in combination, an electrode for electrical connection with the line conductor having a flat terminal surface, and an opposed electrode for electrical connection with the ground, the latter electrode 40 comprising a hollow rod or tube having its terminal furnished with points in proximity to but out of contact with said flat surface, and an insulating-shell inclosing said electrodes.

45 4. An arrester having, in combination, circuit terminals or electrodes and an insulating-shell inclosing the same and rigidly holding them in proper spaced relation, the line-electrode having a grooved cap and adapted 50 for attachment to and in direct contact with the line conductor.

5. An arrester having, in combination, alined circuit terminals or electrodes and a tubular insulating-shell inclosing portions of 55 the same and rigidly holding them in proper spaced relation, one electrode having a series of points closely adjacent to but not in contact with the other electrode.

6. An arrester having, in combination, an 60 electrode for connection with the line conductor having a terminal surface where the electrical charge is of maximum density, and an opposed hollow electrode for connection with the ground having its terminal end furnished 65 with points projecting into the region of great-

est density, but out of contact with said first electrode.

7. An arrester having, in combination, circuit terminals or electrodes arranged end to end or in alinement to form a gap, the ground-electrode being of tubular form. 70

8. An arrester having, in combination, circuit terminals or electrodes arranged to form a gap, the ground-electrode being of tubular form, and an insulating-shell inclosing and 75 connecting said electrodes.

9. An arrester having, in combination, an electrode for connection with the line conductor, a hollow electrode for connection with the ground having its terminal opposed to 80 the terminal of the first electrode and spaced to form a spark-gap, and an insulating-shell inclosing the electrodes and containing a relatively long portion of the hollow ground-electrode. 85

10. An arrester having, in combination, an electrode for connection with the line conductor, a tubular electrode for connection with the ground having its terminal opposed to the terminal of the first electrode and 90 spaced to form a spark-gap, and an insulating-shell inclosing the electrodes, the line-electrode having a flat terminal surface and the ground-electrode having a serrated terminal edge in proximity to such surface. 95

11. An arrester having, in combination, a cap having means for direct contact with the line-wire and having a depending stud and a depending peripheral flange, a ground-electrode alined with said stud and having its 100 terminal arranged with relation thereto to form a gap, and a tubular insulating shell inclosing said stud and ground electrode and having its upper end fitted in the under side of the cap and embraced by the flange there- 105 of, forming a fluid-tight joint.

12. An arrester having, in combination, a cap having means for direct contact with the line-wire and having a depending stud and a depending peripheral flange, said stud constituting a circuit-terminal, a ground-rod 110 having its terminal arranged with reference to said stud to form a gap, and a tubular insulating-shell inclosing and connecting said stud and ground-rod and having its upper 115 end fitted in the under side of said cap, forming a fluid-tight joint.

13. An arrester comprising a rigid unitary structure having a gap and having a cap with a groove to receive the line-wire and with a 120 transverse hole to allow a tie-wire to be inserted therethrough for fastening the cap to the line-wire.

14. An arrester, comprising a tubular insulation-shell, a metallic cap at one end thereof having a transverse groove adapted to receive the line-wire and a transverse hole adapted to receive the tie-wire for securing said cap to the line-wire, said cap having an 125 electrode secured in said tubular shell, and an 130

opposed ground-electrode secured in said shell and spaced with relation to the former to produce a gap.

15. An arrester comprising a tubular insulation-shell, a metallic cap at one end thereof having a stud secured in the said shell and constituting a line-electrode, said electrode having a flat terminal surface, and a ground-electrode secured in said shell consisting of a metallic tube having its terminal furnished

with a series of points in close proximity to but not in contact with the line-electrode.

In testimony whereof we affix our signatures in presence of two witnesses.
